B. D. FORD.

REAMER.

APPLICATION FILED NOV. 8, 1915.

1,207,735.

Patented Dec. 12, 1916.

UNITED STATES PATENT OFFICE.

BION D. FORD, OF CLEVELAND, OHIO.

REAMER.

1,207,735.

Specification of Letters Patent. Patented Dec. 13, 1916.

Application filed November 8, 1915. Serial No. 60,194.

To all whom it may concern:

Be it known that I, BION D. FORD, a citizen of the United States, residing at Cleveland, in the county of Cuyahoga and State of Ohio, have invented a certain new and useful Improvement in Reamers, of which the following is a full, clear, and exact description, reference being had to the accompanying drawings.

10. This invention relates to reamers or cutting tools for metal working of the type having a head, provided with longitudinal grooves arranged radially, and blades held in said grooves.

15. The object of the invention is to provide an improved tool in which the blades may be easily placed or removed; to provide improved means for fastening the blades in the grooves, said means consisting of wedges 20 which are driven in between the inclined walls of the grooves and the inclined sides of the blades; and to provide improved means for the easy removal of said pins or keys, enabling them to be quickly released 25 or backed out.

With these and other objects in view, the invention is hereinafter described and is illustrated in the accompanying drawings, in which—

30. Figure 1 is an elevation of the tool. Fig. 2 is a section on the line 2—2 of Fig. 1. Fig. 3 is a section on the line 3—3 of Fig. 1. Fig. 4 is a perspective of one of the blades. Fig. 5 is a perspective of one of the locking keys 35 or pins. Fig. 6 is a partial sectional view of a shell reamer forming a modification.

Referring specifically to the drawings, 6 indicates the shank of the tool and 7 the head thereof, reduced to form a neck 8 between the shank and the head, through 40 which neck are cross or diametrical bores or openings 9. The head is slotted lengthwise, the slots being radially arranged. The back wall 10 of each slot is flat and parallel to the axis of the tool. At its front wall, the slot has a groove 11 the surface of which is conical or curved and which extends at an 45 inclination to the axis of the tool, as shown at 12, tapering inwardly or toward the shank, and these grooves open at their ends into the cross bores 9 in the neck. The upper or inner ends of the grooves are closed as shown at 30 to sustain the thrust or longitudinal pressure on the blades.

50. The blades 13 are solid pieces of steel properly shaped to form the cutting edges,

and these blades fit in the slots in the head. The back of each blade is flat and rests against the back wall 10 of the slot. The front wall 14 of the blade is inclined or 60 tapered off toward the inner end thereof, with a shoulder 15 extending along the tapered surface adjacent the outer or cutting edge of the blade. Each locking pin or key 16 has a curved or segmental surface 17 to 65 fit the groove 11 and has a flattened or truncated surface 18 to fit the adjacent inclined surface 14 of the blade, and the key is long enough to project at its inner end, into the cross bore 9, as shown in Figs. 1 and 3. 70 When the blades are at opposite points, the keys will project into each bore.

The tool is assembled by inserting the blades in the slots and driving the wedge keys into the key way or grooves endwise, 75 the keys thereby engaging the blades with a wedging action and locking the blades in the head. It is to be noted, also, that the surfaces 14 of the blades incline transversely as well as longitudinally, and the keys therefore grip the blades with a lateral wedging action as well as a longitudinal wedging action, the engaging surfaces being at an angle to the radius as well as to the axis of the head. This locks the blades against 80 either longitudinal or radial movement, pressing the same firmly to their seats against the back and inner walls of the slots.

An important feature of the construction follows from the projection of the inner 90 ends of the keys into the bores 9, for the keys may be easily loosened by inserting a bevel tool or bar into the said bores, to loosen and knock out the keys and permit the removal of the blades, and the knocking out 95 tool will act directly on the ends of the keys.

In the modification shown in Fig. 6 the shell 20 has a circumferential flange 21 at the upper ends of the grooves in which the keys are inserted, and the upper or inner 100 ends of the keys extend through suitable holes in said flange, as shown at 22, permitting the keys to be tapped and loosened by a hammer or the like, for the purpose of removing the blades.

The number of blades may be varied as desired and various other changes in the parts may be made, within the scope of the following claims.

Having thus described my invention, what 110 I claim is:—

1. A cutter head having a slot therein, a

- blade in the slot having a flat longitudinally and laterally inclined surface, and a wedge key in the slot, having a flat inclined surface fitting against the said inclined surface of the blade, to lock the same in the slot.
2. A cutter head having a slot therein, a blade in the slot having a surface inclined both to the axis and the radius of the head, and a wedge key in the slot, having a flat inclined surface fitting against said surface of the blade.
3. A cutter head having a slot therein, one wall of the slot having a longitudinally inclined groove, a blade fitting in the slot and having a flat surface opposite the groove inclined both to the axis and the radius of the head, and a wedge key in the groove, fitting against said surface.
4. A cutter head having a slot therein, the front side wall of the slot having a tapered groove, a blade fitting in the slot and having a flat side surface inclined longitudinally and transversely, and a wedge key in the groove having a flat side, fitting against said surface.
5. A cutter head having a recess therein open at both ends and one side wall of which is tapered longitudinally, a blade fitting in said recess, and a wedge key in said recess, beside the blade, the small end of the key projecting through and beyond the opening at one end of the recess whereby it may be backed out by pressure applied to said end.
6. A cutter head having a longitudinal slot therein closed at its inner end and a groove beside the slot, open at both ends, a blade in the slot and abutting at its end against the closed end of the slot, and a wedge key in the groove, binding against the blade and exposed at its small end at the opening at one end of the groove.
7. A cutter head having a longitudinal slot therein closed at its inner end, a groove beside the slot open at both ends, and an opening communicating with the inner end of the groove, a blade in the slot, and a wedge key in the groove, beside the blade, said key projecting at its inner end into said opening, whereby the key may be backed out by a tool inserted into said recess.
8. A cutter head having longitudinal slots, grooves beside said slots, and an opening through the head and communicating with the inner ends of said grooves, blades in the slots, and wedge keys for the blades, in the grooves, said keys projecting at their inner smaller ends into said opening, for the purpose stated.
- In testimony whereof, I hereunto affix my signature.

BION D. FORD.
